[57] CLAIM

The ornamental design for a golf swing practice device,
as shown and described.

DESCRIPTION

FIG. 1 is a side elevational view of a golf swing practice device showing my new design;

FIG. 2 is a perspective view thereof as viewed from the bottom; and,
FIG. 3 is a perspective view thereof as viewed from the top.

The broken lines illustrating a man in FIG. 1 are for
illustrative purposes and form no part of the claimed
design.

FIG. 1

FIG. 2

FIG. 3
